WELL-DRILLING PUMP UNIT

Leonard K. Heiner, Wichita, Kans.

Application July 14, 1941, Serial No. 402,395

19 Claims. (Cl. 255—64)

My invention, which relates to the art of deep well drilling, has especially for its objects to provide: apparatus for drilling deep wells at a fair rate of speed; apparatus by the use of which the nature of the formation penetrated can be ascertained; apparatus by the use of which it becomes possible to cement the hole cave-in-proof and water-tight in one operation; apparatus that may be used to produce the well at any time, making it possible to determine the production without coming out of the hole with the drilling equipment.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 (composed of Figs. 1^A, 1^B, 1^C, 1^D, joined on the lines A—A, B—B and C—C) is a vertical longitudinal section of my apparatus, parts being broken away.

Figs. 2 to 10, inclusive, are enlarged cross sections respectively on the lines 2—2, 3—3, 4—4, 5—5, 6—6, 7—7, 8—8, 9—9 and 10—10 of Fig. 1.

Fig. 11 (composed of Figs 11^A and 11^B joined on the lines B—B) is a side elevation of Fig. 1 turned 90°.

Fig. 12 is a detail elevation of the lower valve and valve body viewed 90° from the view of Fig. 1^A.

Fig. 13 is a cross section on the line 13—13 of Fig. 12.

Fig. 14 is a detail vertical section of the relief valve unit.

Fig. 15 is an elevation of the same, viewed 90° from the view of Fig. 14.

Fig. 16 is a detail vertical section of the bumper, the cylinder cap and part of the cylinder separated.

Figs. 17, 18 and 19 are, respectively, cross sections on the lines 17—17, 18—18 and 19—19 of Fig. 16.

Fig. 20 is an enlarged vertical section on the line 20—20 of Fig. 10.

In the drawings, which illustrate a preferred embodiment of my invention, 1 represents the shank of the bit proper 3, and 2 indicates the hole or passage through the bit. The particular construction of bit used is not per se a part of the invention, but I prefer to use a bit of the

construction shown. As will be seen by reference to Fig. 1^A, the bit has wings 4 whose under edges incline downwardly toward the axis of the bit. The wings 4 carry circumferentially disposed cutter blades 5 having teeth 6.

The cutter is connected to the lower end of the outer cylinder 8 by means of a tool joint 7 into which the upper threaded end of the shank 1 is screwed. The joint 7 is welded at w to the cylinder 8 and forms therewith a unitary structure. At its upper end the cylinder 8 is welded to a cylinder cap 8^a, which is made in two halves and has a lower reduced portion 8^c to fit into the upper end of the cylinder 8, and an upper reduced portion 8^b to fit into the skirt 14^b of an upper bumper 14.

The bumper 14 and the cap 8 each have a cable guide bore 15, a discharge pipe guide bore 17 with key grooves 17^a and a cable ferrule receiving bore 16 (see Fig. 16). The upper end of the bumper 14 is bevelled for a purpose presently understood.

Within the cylinder 8 is a spring seat 9, which may be formed of a collar rigidly secured in the cylinder 8 in any approved way, as for example by welding, so as to form with the cylinder an integral structure (see Fig. 1^B). 10 is a packing of oil-resisting rubber or other suitable substance, and 11 indicates the upper packing sleeve which also fits in the cylinder 8 and is secured thereto as an integral structure (Figs. 1^B and 1^C). The sleeve 11 has its upper end bevelled as at 10^a. A packing ring 12 is interposed between the spring 13 and the packing 10 (Fig. 1^B).

35 A cable 29 passes down through the passage 15 and is secured to a ferrule 31, located in bore 16, a ball bearing 30 being interposed between the ferrule 31 and the bumper 14 (Fig. 1^C).

Screwed into the tool joint 7 is the lower ball-valve unit which comprises the valve body 32 having a valve seat 34 for the ball valve 33, and having an apertured neck 35, the apertures of which, preferably, incline downwardly-outwardly, and having a transverse valve entrant opening 33^a. An inner cylinder 36 is welded to the neck 35 and projects into the inner plunger 37 (Fig. 1^A).

The inner plunger 37 at its upper end has welded, or otherwise fixedly secured to it, an upper ball-valve unit. This unit comprises a valve body 39 having a valve seat for a ball valve 40, and having an apertured neck 41 (the apertures of which, preferably, incline downwardly-outwardly).

A plunger tube 38 has its lower end threaded

as at 38^a to the lower end of the inner plunger 37.

The upper end of the plunger tube 38 is threaded at 49 (Fig. 1^B) to screw onto the threaded end 44^a (Figs. 14 and 15) of the body 44 of the relief valve unit. The body 44 has a liquid discharge passage 50 and an air duct 51. The lower end of the duct 51 is tapped, as at 44^b, and an air cushion pipe 52 is threaded into the same (Fig. 1^B). The upper end of the duct 51 leads into a valve chamber which has a lateral outlet provided with a valve seat 45 and which contains a ball valve 46 and valve spring 47. A plunger 48 on the outside of the body 44 is provided to unseat the valve 46 when desired, as will later more fully appear.

Welded to the body 44 is a discharge tube 42 whose lower end telescopes into the neck 41 with a slip joint as at 43 (Fig. 1^A). Welded to the top of the body 44 is the discharge pipe 17^b which passes through the upper bumper cup 18 and the end block 18^b of the upper bumper cup. The lower end of the cup 18 is bevelled as at 18^a to cooperate with the bevelled end 14^a of the bumper 14 (Fig. 1^D). A rubber bumper composed of discs 19 having staggered holes 20 is located in the cup 18, while a similarly constructed resilient bumper 21, having staggered holes 22, is located in the cylinder 8 below the bumper 14.

The discharge pipe 17^b has wings which lie in the key-ways 17^a, and the pipe 17^b is secured to the cap block 18^b by lock screws 24 and 25 in threaded sockets 23. The parts are so arranged that collar 27 which connects pipe 17^b with stand-pipe 28 through threads 26 bears against 18^b when screws 24, 25 are properly set.

Pipe 28 and cable 29 reach to the surface of the ground and are carried by a suitable turntable at the surface of the ground.

Operation

The combined pump and bit apparatus is let down and the pipe line 28 is held against longitudinal movement while cable 29 is raised and lowered to reciprocate the drill, the stroke being so regulated that normally the bevelled end 14^a of the upper packing sleeve will not engage the plunger 48 and bumper 14 will not engage bumper 19 (on the upstroke), and bumper 21 will not engage the valve body 44 (on the downstroke).

As the drill is worked up and down, it is, at the same time, turned about the axis of the bit by the turntable, giving a churning and chiseling action as the bit works its way into the formation. A pumping action takes place at the same time. On the downstroke of the outer cylinder 8 valve 33 unseats while valve 40 remains seated, as does also valve 46. Through the pump action of the plunger 37 water and the detritus is drawn up hole 2 through lower valve body 32 into the inner cylinder, some water passing through the apertures of neck 35 into the space between the outer and inner cylinders below spring seat 9. As the velocity of the solids passing up through 35 is considerable, only the liquid will flow downwardly-outwardly through the apertures in neck 35, while the solids will rush by the same.

On the upstroke of the cylinder 8 valve 33 will close and valve 40 will open; the downward motion (relative) of inner plunger 36 then forces the water back through the holes in neck 35 and it, together with the water and detritus in the inner cylinder 36, passes up through the upper valve body into the discharge tube (and eventually to the surface through relief valve body 44, discharge pipe 17^b and the string of standpipe 28),

a part of the water passing through the holes in neck 41 into the space between the discharge tube 42 and the inner plunger, compressing the air above it and that in pipe 52 (which air acts as an air spring or ram). This completes a cycle (complete reciprocation of drill bit and cylinder 8).

This reciprocation of cylinder 8 and bit 1 continues until bumper 21 reaches bumper 19 and bumper 21 is reached by valve body 44. Thereupon pipe string 28 is lowered the required distance (one drill stroke length) and the reciprocation of the drill and consequent pumping action continues as before. If desired, pipe 28 may be lowered at a steady rate equal to the depth of the cut made by the bit during each impact.

After a time any air that may be pocketed between the inner cylinder 36 and the outer cylinder 8 will leak away or become absorbed. So also will the air in the space between the discharge tube 42 and the inner plunger 37 and in pipe 52.

In order to replace the air in the space between the tube 42 and plunger 37 and in pipe 2, cable 29 is drawn up higher than the upper limit of its working stroke until the bevelled end 14^a rides up on plunger 48, thereby pressing it in and unseating valve 46. Compressed air is then pumped down standpipe 28 and the water is blown down and out through the drill. Compressed air then passes into the spaces referred to and through pipe 52, duct 51, into outer casing 8 and escaping through the longitudinal slots 53 into the water surrounding the apparatus. When this occurs, cylinder (or casing 8) is lowered to release the plunger 48, whereupon spring 47 plus air pressure, seats valve 46 and closes off escape of air. The air compressor is then operatively disconnected from pipe 28 and the apparatus is again worked, as hereinbefore described.

The water pumped by the apparatus is returned to the hole around the outer cylinder and the bit. When a loose formation is contacted, the water will seek its normal level. Meanwhile the drilling motion, if continued, will return about the same quantity of water to the hole as is pumped out. When the water around the bit has about reached its normal height, then cement is added and a little more water than is being removed, causing the cement to filter into the formation about the hole where, once it comes to rest, it will set, thus making the sand or gravel bed adjacent the hole a cement block. The distance the cement leaves the hole will depend largely on the difference of the internal pressure retained in relation to the outer pressure and the speed of the underground flow. The cement within the water in the hole is kept in circulation with the cuttings which come up to the surface, the cuttings being screened out or otherwise separated from the liquid, only the liquid being returned to the hole.

The fact that the bit is a chisel-type one and is turned as it lifts, eliminates most of the mud that would be formed by other methods.

In practice the turning of the bit takes place on the upstroke. A surface charge pump (not shown) is used to pressure-out artesian flow or any other undesired flow, or to drive the cement farther into the formation surrounding the hole, when desired.

Lime may be used in the water when it is desired to pass up a vein that it may be desirable to re-open.

As the center of the bit is hollow, it will pass a core as well as the coarse cuttings, thereby

eliminating guess-work as to what is being drilled.

The chisel bit will not pack the surrounding wall, making it possible to obtain a better producer well. The shale formation will not be disturbed so far back from the wall, and thus it is left in better condition to stand a dry hole while production is being tested. This test can be made by pumping the hole dry by using my apparatus.

In raising the apparatus from the hole, the entire structure is suspended on the cable; sleeve 11 rides up over plunger 48 to open relief valve 46, upper bumper cup is entered by bumper 14 until bumper 14 engages rubber bumper 19, whereupon the parts come to rest on the cable 15 29 and may be raised by the usual rigging (not shown) at the surface of the ground.

Attention is called to the fact that the cylinder cap 8^a is made in two parts, or split longitudinally, and the upper end of the cylinder 8 is correspondingly split as at 53. The cap 8^a is welded where it fits into the cylinder. This enables the two parts of the cap to be spread apart for the introduction and removal of the cable 29 and ferrule 31. The top end 8^b of the cap is then held together by forcing the skirt 14^b over the same and securing it to the cap by pins or set screws 54.

From the foregoing description, taken in connection with the accompanying drawings, it is thought that the complete construction, operation and advantages of the invention will be clear to those skilled in the art to which it relates.

What I claim is:

1. In apparatus of the class described, a hollow bit, an outer cylinder to the lower end of which the bit is connected, an inner cylinder within and spaced from said outer cylinder, a lower upwardly opening back check valve device connected to and communicating with said inner cylinder at its lower end and communicating with the passage in said bit, an inner plunger fitted over said inner cylinder, an upper upwardly opening back check valve carried by said inner plunger, a discharge tube leading upwardly from said upper back check valve, a plunger tube connected at its lower end to and enclosing said inner plunger, a closure for the upper end of said plunger tube, said closure having a passage communicating with said discharge tube, a discharge pipe leading from said passage to the top of the apparatus and adapted for connection to a standpipe, and means for reciprocating said outer cylinder and bit for effecting a cutting and a pumping operation.

2. In apparatus of the class described, a hollow bit, an outer cylinder to the lower end of which the bit is connected, an inner cylinder within and spaced from said outer cylinder, a lower upwardly opening back check valve device connected to and communicating with said inner cylinder at its lower end and communicating with the passage in said bit, an inner plunger fitted over said inner cylinder, an upper upwardly opening back check valve carried by said inner plunger, a discharge tube leading upwardly from said upper back check valve, a plunger tube connected at its lower end to and enclosing said inner plunger, a closure for the upper end of said plunger tube, means for establishing an air cushion between said plunger tube and said discharge tube, said closure having a passage communicating with said discharge tube, a discharge pipe

leading from said passage to the top of the apparatus and adapted for connection to a standpipe, and means for reciprocating said outer cylinder and bit for effecting a cutting and a pumping operation.

3. In apparatus of the class described, a hollow bit, an outer cylinder to the lower end of which the bit is connected, an inner cylinder within and spaced from said outer cylinder, a lower upwardly opening back check valve device connected to and communicating with said inner cylinder at its lower end and communicating with the passage in said bit, an inner plunger fitted over said inner cylinder, an upper upwardly opening back check valve carried by said inner plunger, a discharge tube leading upwardly from said upper back check valve, a plunger tube connected at its lower end to and enclosing said inner plunger, a closure for the upper end of said plunger tube, said closure having a passage communicating with said discharge tube, a discharge pipe leading from said passage to the top of the apparatus and adapted for connection to a standpipe, means for reciprocating said outer cylinder and bit for effecting a cutting and a pumping operation, and means for establishing an air cushion within said inner cylinder.

4. In apparatus of the class described, a hollow bit, an outer cylinder to the lower end of which the bit is connected, an inner cylinder within and spaced from said outer cylinder, a lower upwardly opening back check valve device connected to and communicating with said inner cylinder at its lower end and communicating with the passage in said bit, an inner plunger fitted over said inner cylinder, an upper upwardly opening back check valve carried by said inner plunger, a discharge tube leading upwardly from said upper back check valve, a plunger tube connected at its lower end to and enclosing said inner plunger, a closure for the upper end of said plunger tube, means for establishing an air cushion between said plunger tube and said discharge tube, said closure having a passage communicating with said discharge tube, a discharge pipe leading from said passage to the top of the apparatus and adapted for connection to a standpipe, means for reciprocating said outer cylinder and bit for effecting a cutting and a pumping operation, and means for admitting and exhausting water to and from said outer cylinder between it and said inner cylinder.

5. In apparatus of the class described, an outer cylinder, a hollow bit secured to the lower end of said cylinder, a cylinder cap, an upper bumper, said bumper projecting upwardly from the cylinder cap, said bumper having a cable passage and a discharge pipe passage, a cable ferrule on the lower end of said cable and a swivel bearing between said ferrule and said bumper, an upper bumper cup having a passage for said cable and having a discharge pipe receiving opening, said cup adapted for telescoping over said upper bumper, a discharge pipe connected to said cup and passing down into said outer cylinder through said upper bumper, a relief valve unit connected to the lower end of said discharge pipe and having a through passage communicating with said discharge pipe, a plunger tube carried by said unit, a back check valve unit carried by said plunger tube, a discharge tube communicating with said back check valve unit and the through passage of said relief valve unit, said relief valve unit including a relief-valve-controlled duct communicating with the space be-

tween said plunger tube and said discharge tube, an inner cylinder telescoping into said plunger tube, a lower back check valve between said inner cylinder and said bit, means for establishing an air spring in the space between said plunger tube and said discharge tube, and means for opening said relief valve to effect communication between the air spring space and the outside of the apparatus.

6. In apparatus of the class described, an outer cylinder, a hollow bit secured to the lower end of said cylinder, a cylinder cap, an upper bumper, said bumper projecting upwardly from the cylinder cap, said bumper having a cable passage and a discharge pipe passage, a cable ferrule on the lower end of said cable and a swivel bearing between said ferrule and said bumper, an upper bumper cup having a passage for said cable and having a discharge pipe receiving opening, said cup adapted for telescoping over said upper bumper, a resilient bumper within said cup, a discharge pipe connected to said cup and passing down into said outer cylinder through said upper bumper, a relief valve unit connected to the lower end of said discharge pipe and having a through passage communicating with said discharge pipe, a plunger tube carried by said unit, a back check valve unit carried by said plunger tube, a discharge tube communicating with said back check valve unit and the through passage of said relief valve unit, said relief valve unit including a relief-valve-controlled duct communicating with the space between said plunger tube and said discharge tube, an inner cylinder telescoping into said plunger tube, a lower back check valve between said inner cylinder and said bit, means for establishing an air spring in the space between said plunger tube and said discharge tube, means for opening said relief valve to effect communication between the air spring space and the outside of the apparatus, and a resilient bumper in said outer cylinder between said relief valve unit and said upper bumper.

7. In apparatus of the class described, an outer cylinder, a hollow bit secured to the lower end of said cylinder, a cylinder cap, an upper bumper, said bumper projecting upwardly from the cylinder cap, said bumper having a cable passage and a discharge pipe passage, a cable ferrule on the lower end of said cable and a swivel bearing between said ferrule and said bumper, an upper bumper cup having a passage for said cable and having a discharge pipe receiving opening, said cup adapted for telescoping over said upper bumper, a discharge pipe connected to said cup and passing down into said outer cylinder through said upper bumper, a relief valve unit connected to the lower end of said discharge pipe and having a through passage communicating with said discharge pipe, a plunger tube carried by said unit, a back check valve unit carried by said plunger tube, a discharge tube communicating with said back check valve unit and the through passage of said relief valve unit, said relief valve unit including a relief-valve-controlled duct communicating with the space between said plunger tube and said discharge tube, an inner cylinder telescoping into said plunger tube, a lower back check valve between said inner cylinder and said bit, means for establishing an air spring in the space between said plunger tube and said discharge tube, means for opening said relief valve to effect communication between the air spring space and the outside of the apparatus, and means for admitting

water to and exhausting the same from said outer cylinder between it and said inner cylinder, said air spring giving to the apparatus the pumping action of a hydraulic ram.

5. In apparatus of the class described, a pipeline for extending down into a well, a plunger device with a back check valve carried by said pipe-line, an outer reciprocating cylinder enclosing and cooperating with said plunger device,

10 a hollow bit and a back check valve carried by said cylinder, and means by which said outer cylinder may be reciprocated while said pipe-line and plunger device remain stationary.

9. In apparatus of the class described, a pipeline for extending down into a well, a plunger device with a back check valve carried by said pipe-line, an outer reciprocating cylinder enclosing and cooperating with said plunger device, a hollow bit and a back check valve carried by said cylinder, means by which said outer cylinder may be reciprocated while said pipe-line and plunger device remain stationary, and means for establishing an air spring for cooperation with the water passing up through said plunger device to act as a hydraulic ram.

10. In apparatus of the class described, a pipeline for extending down into a well, a plunger device with a back check valve carried by said pipe-line, an outer reciprocating cylinder enclosing and cooperating with said plunger device, a hollow bit and a back check valve carried by said cylinder, means by which said outer cylinder may be reciprocated while said pipe-line and plunger device remain stationary, an upper bumper on said cylinder, and an upper bumper cup carried by said pipe-line to telescope over said bumper, said means by which said cylinder may be reciprocated comprising a cable passed through said cup and connected to said cylinder.

40 11. In apparatus of the class described, a pipeline for extending down into a well, a plunger device with a back check valve carried by said pipe-line, an outer reciprocating cylinder enclosing and cooperating with said plunger device, a hollow bit and a back check valve carried by said cylinder, means by which said outer cylinder may be reciprocated while said pipe-line and plunger device remain stationary, an upper bumper on said cylinder, an upper bumper cup carried by said pipe-line to telescope over said bumper, said means by which said cylinder may be reciprocated comprising a cable passed through said cup and connected to said cylinder, and a lower bumper in said cylinder for cooperation with a part of said plunger device, said bumpers serving to limit the strokes of said cylinder with respect to said plunger device.

12. In apparatus of the class described, an outer cylinder, a hollow bit carried by said cylinder at its lower end, a cylinder cap and an upper bumper for the upper end of said cylinder and having offset passages for a discharge pipe and a cable respectively, a cable passing through the cable passage and swivelly anchored to said cylinder cap, a discharge pipe passing through the discharge passage into the cylinder, an upper bumper secured to said discharge pipe for cooperation with the upper bumper of said cylinder and having a passage for said cable, and means within the cylinder and cooperating with said discharge pipe for pumping liquid and cuttings up through said bit to and through said discharge pipe.

13. In apparatus of the class described, an outer cylinder, a hollow bit carried by said cylinder at its lower end, a cylinder cap and an upper bumper

for the upper end of said cylinder and having offset passages for a discharge pipe and a cable respectively, a cable passing through the cable passage and swivelly anchored to said cylinder cap, a discharge pipe passing through the discharge passage into the cylinder, an upper bumper secured to said discharge pipe for cooperation with the upper bumper of said cylinder and having a passage for said cable, and means within the cylinder and cooperating with said discharge pipe for pumping liquid and cuttings up through said bit to and through said discharge pipe, said last named means including a hydraulic ram.

14. In apparatus of the class described, an outer cylinder, a hollow bit carried by said cylinder at its lower end, a cylinder cap and an upper bumper for the upper end of said cylinder and having offset passages for a discharge pipe and a cable respectively, a cable passing through the cable passage and swivelly anchored to said cylinder cap, a discharge pipe passing through the discharge passage into the cylinder, an upper bumper secured to said discharge pipe for cooperation with the upper bumper of said cylinder and having a passage for said cable, a lower back check valve unit carried by said cylinder and having a passage communicating with said bit, an inner cylinder carried by said back check valve unit, said unit including a perforated neck for effecting communication with the space in the outer cylinder surrounding the inner cylinder, means for closing the upper end of said space, an inner plunger device within said outer cylinder and into which said inner cylinder telescopes, said inner plunger device including an upper back check valve unit, having a perforated neck, and a plunger tube enclosing said upper back check valve unit, a duct effecting communication between said upper back check valve unit and said discharge pipe, and means for closing off above the aforesaid neck the space between said duct and said plunger tube, thereby to provide an air spring for hydraulic ram action.

15. In apparatus of the class described, an outer cylinder, a hollow bit carried by said cylinder at its lower end, a cylinder cap and an upper bumper for the upper end of said cylinder and having offset passages for a discharge pipe and a cable respectively, a cable passing through the cable passage and swivelly anchored to said cylinder, a discharge pipe passing through the discharge passage into the cylinder, an upper bumper secured to said discharge pipe for cooperation with the upper bumper of said cylinder and having a passage for said cable, a lower back check valve unit carried by said cylinder and having a passage communicating with said bit, an inner cylinder carried by said back check valve unit, said unit including a perforated neck for effecting communication with the space in the outer cylinder surrounding the inner cylinder, means for closing the upper end of said space, an inner plunger device within said outer cylinder and into which said inner cylinder telescopes, said inner plunger device including an upper back check valve unit, having a perforated neck, a plunger tube enclosing said upper back check valve unit, a duct effecting communication between said upper back check valve unit and said discharge pipe, means for closing off above the aforesaid neck the space between said duct and said plunger tube, thereby to provide an air spring for hydraulic ram action, and means for opening said space to atmosphere at will.

16. In apparatus of the class described, an

outer cylinder, a hollow bit carried by said cylinder, a discharge pipe and a cable passed down into said cylinder, means to anchor said cable to said cylinder, a lower back check valve unit carried by said cylinder and having a passage communicating with said bit, an inner cylinder carried by said back check valve unit, said unit including a perforated neck for effecting communication with the space in the outer cylinder surrounding the inner cylinder, means for closing the upper end of said space, an inner plunger device within said outer cylinder and into which said inner cylinder telescopes, said inner plunger device including an upper back check valve unit, having a perforated neck, a plunger tube enclosing said upper back check valve unit, a duct effecting communication between said upper back check valve unit and said discharge pipe, and means for closing off above the aforesaid neck the space between said duct and said plunger tube, thereby to provide an air spring for hydraulic ram action.

17. In apparatus of the class described, an outer cylinder, a hollow bit attached to the lower end of said cylinder, the upper end of the cylinder being longitudinally split, a two-part cylinder cap having a reduced lower end to fit into the top of said outer cylinder with its parting plane passing through the cylinder split, means permanently securing the cap to the outer cylinder, said cap having a reduced upper end, an upper bumper having a skirt fitted over the upper end of said cap, means securing said skirt to said cap, an upper bumper cup, a cable passed through said upper bumper cap and continued into and anchored to said cap, a discharge pipe also passing through said upper bumper cup, said upper bumper and said cap, and means connected to said discharge pipe and mounted on said outer cylinder and cooperating with said outer cylinder for pumping up the cuttings made by the bit.

18. In apparatus of the class described, an outer cylinder having a cap at its upper end and a tool joint at its lower end, a hollow drill secured to said joint, a lower back check valve unit including a valve body secured to said joint and having a through passage controlled by a valve having a neck with downwardly-outwardly inclined apertures, an inner cylinder secured at its lower end to said neck and spaced from said outer cylinder, an inner plunger whose lower end telescopes said inner cylinder, an upper back check valve unit carried by said inner plunger at its upper end and including a valve body having a through passage controlled by a valve and having a neck with downwardly-outwardly inclined apertures, a plunger tube whose lower end is connected with and carries said inner plunger, a relief valve body having a through passage, a discharge tube carried by said relief valve body and communicating with the neck of said upper back check valve body, said relief valve body having a relief-valve-controlled passage for effecting communication between the atmosphere and the space between said plunger tube and said discharge tube, means normally holding the relief valve closed, means operable by movement of said outer cylinder along the axis of the inner cylinder for opening said relief valve when desired, a discharge pipe leading from the through passage of said relief valve body to and through the top of said outer cylinder, and means for reciprocating said outer and inner cylinders while said inner plunger, said plunger tube relief valve and said discharge pipe remain stationary.

19. In apparatus of the class described, an outer cylinder having a cap at its upper end and a tool joint at its lower end, a hollow drill secured to said joint, a lower back check valve unit including a valve body secured to said joint and having a through passage controlled by a valve having a neck, an inner cylinder secured at its lower end to said neck and spaced from said outer cylinder, an inner plunger whose lower end telescopes said inner cylinder, an upper back check valve unit carried by said inner plunger at its upper end and including a valve body having a through passage controlled by a valve and having a neck, a plunger tube whose lower end is connected with and carries said inner plunger, a relief valve body having a through passage, a discharge tube carried by said relief valve body and communicating with the neck of said upper back check valve body, said relief valve body

having a relief-valve-controlled passage for effecting communication between the atmosphere and the space between said plunger tube and said discharge tube, means normally holding the relief valve closed, means operable by movement of said outer cylinder along the axis of the inner cylinder for opening said relief valve when desired, a discharge pipe leading from the through passage of said relief valve body to and through the top of said outer cylinder, means for reciprocating said outer and inner cylinders while said inner plunger, said plunger tube relief valve and said discharge pipe remain stationary, and means for establishing an air spring in communication with the liquid passages above the upper back check valve to set up a hydraulic-ram action when the apparatus is in use.

LEONARD K. HEINER.
